CLAIM

The ornamental design for a mobile communications device with handle members, as shown and described.

DESCRIPTION

FIG. 1 is a perspective view of a mobile communications device with handle members showing my new design;

FIG. 2 is a bottom view thereof;

FIG. 3 is a top view thereof;

FIG. 4 is a right side view thereof, the left side being a mirror image thereof; and,

FIG. 5 is back surface view thereof.

The broken lines are directed to environment and are for illustrative purposes only; the broken lines form no part of the claimed design.
